UNITED STATES PATENT OFFICE.

JOHN D. PUGH, OF MOUNT WASHINGTON, MARYLAND.

POURING DEVICE FOR HOT-METAL CONTAINERS.

Application filed March 30, 1923. Serial No. 628,873.

To all whom it may concern:

Be it known that I, JOHN D. PUGH, a citizen of the United States, and residing at Mount Washington, Baltimore, Maryland, have invented certain new and useful Improvements in Pouring Devices for Hot-Metal Containers, of which the following is a specification.

This invention relates to pouring devices for hot metal containers.

In the manufacture of iron and steel, containers or ladles adapted to hold molten metal have long been in use for transferring metal from place to place, in which case the containers are mounted on wheel trucks, or for receiving the molten metal from the furnace and pouring into various smaller receptacles, in which case the containers may be stationary. A thoroughly efficient container of this character is disclosed in Patent No. 1,251,282 issued to me December 25, 1917. This container is of the closed body type, that is, the metal held therein is completely enclosed by the walls of the container except for pouring openings in the top, which openings may be closed by lids, if desired. Other types of ladles or containers have been used but such containers have not been of the closed body type, the upper surface of the metal being exposed to the air, allowing heat to rapidly escape from the body of the metal so that it may remain in the container in a molten condition for only a relatively short length of time.

The closed body container invented by me may be either mounted on a car truck or upon a stationary frame in any suitable manner but is generally provided with two pairs of aligned trunnions about either set of which the container body may be tilted in the frame bearings in which the trunnions rest, to discharge the metal through either of the two top pouring spouts into a receptacle or trough to one side of the same.

It is found desirable, under some circumstances, to pour the hot metal into a trough located to one side of the container at a relatively high level as compared with the position of the container when at rest. In many cases pig casting machines, or other devices, have their receiving ends placed above the track level supporting the hot

metal car. This is generally done to avoid placing the machinery in a pit, which is difficult to drain, or objectionable for other reasons. Wherever for any reason therefore, the receiving trough is high relatively to the track, it is necessary to have the car spout pour in a high position.

It has heretofore been suggested that the contents of hot metal containers of the open top type may be emptied into a trough positioned at a relatively high level by providing a stand positioned adjacent the container and in position to support the same, the container being first tilted on the main container trunnions until the stand is engaged by an auxiliary trunnion or bearing on the container and is then further tilted about the bearing or trunnion on the upper end of the stand as an axis. These stands are particularly useful when the container is mounted on a car truck.

Such stands heretofore suggested have been more or less rigid and inflexible in adapting themselves to variations of car track alignment and, if the latter becomes out of true it is difficult to correctly register the mutually engaging portions of container and stand. Also owing to the fact that the container turns about an axis at or near the lip of the container spout, the said lip does not travel laterally very far over the edge of the receiving trough, and the flowing metal tends to pour more nearly in one spot in the trough and to wear away the same.

There are two principal objects of the present invention, the first being to provide a flexible pouring device to cooperate with a container of either the open or closed body type by means of which the contents of the container may be discharged at a relatively high level as compared with the position of the container when at rest, and the second object being to provide a pouring device which is particularly adapted to advance the spout laterally over the edge of the receiving trough.

While I have illustrated in the drawings and will describe in detail below, the invention especially adapted to assist in the tilting and emptying of a container of exactly circular cross section, it will be apparent that the side support may be used

with containers of other cross sectional formations, and is not limited in this respect, the forms of the invention illustrated in the drawings being given by way of example only.

5 In the drawings:

Figure 1 is a side elevation of a container such as disclosed in my prior patent, mounted on a car truck, and showing a lug secured 10 to its side, which lug cooperates with the pouring stand positioned beside the track in the pouring operation;

Figure 2 is an end elevation of the container, showing the pouring stand, portions 15 of the car being omitted for the sake of clearness, different positions of the container during the pouring operation being shown in dot and dash lines;

Figure 3 is a front elevation of the stand; 20 Figure 4 is a view similar to Figure 2 but showing a modified form of stand;

Figure 5 is a view similar to Figure 4 but showing a slightly modified form of pouring stand and showing the container as being 25 mounted on a stationary frame instead of car truck;

Figure 6 is a section on line 6—6 of Figure 2;

Figure 7 is a similar view through a stand 30 of slightly modified construction;

Figure 8 is a small scale end elevation of the container showing a second means for mounting the same on a stationary frame; and

Figure 9 is a view showing the pouring stand adapted to cooperate with a container of different type from that illustrated in Figures 1 to 8 inclusive.

Referring first to the form of the invention illustrated in Figures 1, 2, 3 and 6, it will be seen that the pouring stands there illustrated are particularly adapted to cooperate with a closed body container which is mounted on a car truck. The container body 10 is provided with two sets of aligned trunnions 11, which rest in bearings 12 supported upon and extending transversely of the car sills 13. These sills may be straight, as shown in Figure 1 or of the drop frame type. The car truck is mounted on rails 14 and the base 15 is located beside the track, as shown in Figure 2, to support the pouring stand S. The stand S may be formed in various ways but as shown 55 comprises spaced uprights 16 suitably braced, and to the faces of which are secured bearing blocks 17. These blocks are provided with bearing surfaces 17' arranged in a vertical plane and have central vertical grooves 17² therein. Chains or other flexible members 18 lie in these grooves, the upper ends of these chains being adjustably secured by bolts 19 to a cross piece 20 mounted at the upper end of the stand and having their lower ends secured to a

suspended member or socket 21. This member has a groove 22 therein which is preferably undercut as shown in Figure 2, the walls of the socket flaring outward as shown in Figure 3, so that they may be said to be bell mouthed. The member 21 can be adjusted vertically through limited distances by means of the screw bolts 19 and horizontally by means of shims or screw bolts N' extending through nuts N 75 secured to the stand.

The groove 22 of member 21 is adapted to receive a rounded rib or lug 23 rigidly and strongly secured to the wall of the container 10 and substantially in the same 80 plane as the trunnions 11. This lug 23 has tapered or pointed ends 24 which find ready entrance into the bell mouthed ends of groove 22 of the suspended member 21 when the car is moved into pouring position 85 opposite the stand S from either direction.

With the container in pouring position as shown in Figure 2, a sling or cable from an overhead crane or power apparatus is attached to the container body at 25 and a vertical upward pull exerted thereon. The trunnions 11 immediately leave their socket bearings and the entire container commences to rotate about its right hand point of suspension, that is, the lug 23 rotates in groove 22. This rotation continues until the container body reaches the position indicated in dot and dash lines (Figure 2), where the rounded surface thereof first makes contact with the bearing surface 17' 100 of the stand. Further lifting by the crane or hoist causes the container to roll upwardly along these bearing surfaces and this movement may be continued until the container has rotated approximately 105 through 90° into the dotted line position (Figure 2), the axis of the bottom pouring spout 10' being then horizontal so that no metal can remain in the container.

A trough 27 receives the molten metal and conveys it to the casting head or wherever needed. After the container has been emptied it may be lowered until the trunnions 11 are again seated in their bearings. The car may be then drawn along the track 110 by an engine and the lug 23 will automatically disengage itself from the suspended member 21. During the raising movement of the container the chains 18 will partially wrap themselves around the container body 115 and then unwrap as the container descends. It will be seen that there is no initial rotation of the container about either pair of trunnions 11, but that the container immediately starts to rotate about the lug 120 23 as it is lifted, thus promoting the speed of operation and preventing jar and back and forth flow of the hot metal as is frequently the case where the container rotates first on its trunnions and then makes 125 130

contact with the pouring stand. It will be further seen that all practical variations in track alignment are provided for in the bell mouth ends of socket 21, which has 5 vertical and horizontal adjustment, and tapering ends of lug 23, so that these members can always be made to register with certainty and the flexibility before mentioned is attained. The lip of the container 10 spout also has considerable lateral movement in pouring.

As can be seen in Figure 6, the member 21 has its rear corners cut away at 30 and lugs 31 are provided to fit in the recesses 15 thus formed. These lugs lock the member 21 against longitudinal horizontal movement as the car moves into pouring position and lug 23 is entering the slot 22.

In Figure 4 the stand S' is shown to have 20 a curved bearing surface 40 so that the container rolls laterally as well as upwardly and the pouring spout 10² is advanced laterally to a considerable distance which is advantageous in many instances for reasons 25 before indicated. In this form of the invention the same socket 22 and lug 23 may be used, but a modification of the same is here shown in which the suspended member 21' is hook shaped and the lug 23' secured 30 to the container is substantially in the form of an oppositely turned hook. The outer ends of member 21' flare outwardly and the ends of lug 23' taper inwardly for the same 35 reasons set forth in connection with members 21 and 23 of the form shown in Figure 2. The member 21' is pivoted at 41 to a flexible member 18' the effective length of which may be adjusted by means of a hand 40 wheel 42. As the container is raised in the pouring operation the initial turning movement will be about the pivot 41 but as soon as the wall of the container strikes the curved bearing surface 40 further movement will be in the nature of a rolling movement 45 on this surface. The suspended member 21' is provided with a rearwardly extending lug 43 which extends into a recess 44 in the face of the stand. The member 21' is thereby locked against longitudinal, horizontal movement as the container is being 50 moved into pouring position.

In Figure 5 the container 10⁴ is shown to be mounted upon stationary supporting rollers 45. The pouring stand S² is in general 55 similar to that shown in Figure 4 with the exception that the suspended member 21² is similar to that illustrated in Figure 2 and cooperates with a lug 23² similar to lug 23 shown in that figure. The mode of 60 operation is exactly the same as before.

In Figure 7 a section of a further modified form of stand is illustrated. In this instance there are two short suspended members or sockets 46 instead of a single continuous member and two separate lugs 47

secured to the container to cooperate therewith. Other modified forms of interengaging members for the container and stand may be designed and employed to suit conditions.

In Figure 9 a hot metal car of common type is shown which is equipped with a rib for engagement with my improved high pouring stand. Shims, indicated at 50, are provided for the purpose of adjusting the 70 socket 51 laterally in case the tracks are not laid in the same true horizontal plane. Adjusting bolts may be employed for this purpose instead of shims, if desired.

Having thus described the invention what 80 is claimed as new and desired to be secured by Letters Patent is:

1. A pouring device of the class described, including in combination, a stand having a 85 stationary surface against which a hot metal container may bear during the pouring operation, and a member supported thereby for movement relatively thereto, which member is adapted to engage one side of the container during the pouring operation and to 90 partially support the same.

2. A pouring device of the class described, including in combination, a stand having a 95 stationary surface extending in a substantially vertical direction against which a hot metal container may bear and move during the pouring operation, and a member supported thereby for movement relatively thereto, which member is adapted to engage one side of the container during the pouring 100 operation and to partially support the same.

3. A pouring device of the class described, including in combination, a stand having 105 two spaced bearing surfaces against which a hot metal container may bear during the pouring operation, and a member supported thereby for movement relatively thereto, which member is adapted to engage one side of the container during the pouring operation and to partially support the same.

4. A pouring device of the class described, including in combination, a stand having a 110 stationary surface against which a hot metal container may bear during the pouring operation, and a member supported thereby for movement relatively thereto, which member is adapted to engage one side of the container during the pouring operation and to partially support the same, said bearing surface being positioned above the container engaging member.

5. A pouring device of the class described, including in combination, a stand having a stationary surface against which a hot metal container may bear during the pouring operation, and a member supported thereby for movement relatively thereto, said member being suspended from a point 125 adjacent the top of the stand, which member 130

is adapted to engage one side of the container during the pouring operation and to partially support the same.

6. A pouring device of the class described, including in combination, a stand having a stationary surface against which a hot metal container may bear during the pouring operation, and a member supported thereby for movement relatively thereto, said member being suspended from said stand by means of a flexible element, and which is adapted to engage one side of the container during the pouring operation and to partially support the same.

7. A pouring device of the class described, including in combination, a stand having a stationary surface against which a hot metal container may bear during the pouring operation, and a member supported thereby for movement relatively thereto, said member being suspended from the stand by two spaced flexible elements and being adapted to engage one side of the container during the pouring operation and to partially support the same.

8. A pouring device of the class described, including in combination, a stand having a stationary surface against which a hot metal container may bear during the pouring operation, and a member supported thereby for movement relatively thereto, which member is adapted to engage one side of the container during the pouring operation and to partially support the same, said member being provided with a groove opening toward the container and adapted to receive a lug on said container.

9. A pouring device of the class described, including in combination, a stand having a stationary surface against which a hot metal container may bear during the pouring operation, and a member supported thereby for movement relatively thereto, which member is adapted to engage one side of the container during the pouring operation and to partially support the same, said groove being bell mouthed at each end for the purpose set forth.

10. A pouring device of the class described, including in combination, a stand having a stationary surface against which a hot metal container may bear during the pouring operation, a member to engage the container, a flexible element whereby said member is supported from said stand, and means for adjusting the effective length of said element.

11. The combination with a hot metal container resting on a car or support having a pouring spout adjacent its top, of a stand adjacent the container and having a surface against which the container may bear, and a flexible connection between the stand and container to partially support the container during the pouring operation.

12. A pouring device of the class described, including in combination, a container having a horizontally disposed lug secured to its side, the ends of said lug being tapered, a stand having a surface against which the container may bear, and a grooved member supported thereon for movement relatively thereto, said member being adapted to receive said lug, for the purpose set forth.

13. The combination with a hot metal container resting on a car or support, of a stand adjacent the container and having a surface against which the container may bear, and means adapted to connect the container and stand, said means and said stand being so designed and constructed that the pouring lip of said container may be given simultaneous vertical and lateral movements in pouring.

14. The combination with a hot metal container having a pouring spout adjacent its top, of means whereby spout may be given simultaneous vertical and horizontal movements in pouring to prevent the molten metal discharged from the spout from striking substantially the same spot throughout the pouring operation.

In testimony whereof I hereunto affix my signature.

JOHN D. PUGH.
